UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

TAKE-UP MECHANISM FOR NARROW-WARE LOOMS.

Application filed April 5, 1922. Serial No. 549,841.

To all whom it may concern:

Be it known that I, ELBRIDGE R. HOLMES, a citizen of the United States, residing at Worcester, in the county of Worcester and 5 State of Massachusetts, have invented a new and useful Take-Up Mechanism for Narrow-Ware Looms, of which the following is a specification.

This invention relates to a take-up mechanism for narrow ware looms, and is particularly designed for use in looms weaving a narrow fabric with one edge or selvage of greater length than the other edge.

It is the object of my invention to provide 10 a take-up mechanism for such a loom so designed that it will engage the fabric closely adjacent the fell of the cloth, and that it will provide a substantially even tension on all parts of the fabric and warp. 15 To the attainment of this object I provide a plurality of tapered take-up rolls, preferably of relatively small diameter and positioned closely adjacent the fell of the cloth. These rolls are positively driven by intermittently actuated feeding devices, and adjacent rolls are rotated in opposite directions.

My invention further relates to arrangements and combinations of parts which will 20 be hereinafter described and more particularly pointed out in the appended claims.

A preferred form of the invention is shown in the drawings in which

Fig. 1 is a front elevation of parts of a 25 narrow ware loom embodying my improvements;

Fig. 2 is a side elevation of the parts shown in Fig. 1;

Fig. 3 is an enlarged rear elevation of the 30 take-up rolls;

Fig. 4 is an enlarged sectional side elevation, taken along the line 4-4 in Fig. 1;

Fig. 5 is an enlarged sectional view taken 35 along the line 5-5 in Fig. 1; and

Fig. 6 is an enlarged sectional view taken along the line 6-6 in Fig. 1.

Referring to the drawings, I have shown 40 portions of the frame 10 of a narrow ware loom, having a breast beam 11, and a lay 12 mounted to swing about a shaft 13 supported in bearings 14 near the bottom of the loom.

A winding shaft 15 is also mounted in bearings in the lower part of the frame 10

and is intermittently rotated by feeding 55 mechanism comprising a ratchet wheel 16 and a feed pawl 17 mounted on a bar 18 adjustably secured to an arm 19 fixed to the end of the shaft 13. The ratchet wheel 16 is fixed to one end of a short shaft 20 mounted 60 in the loom frame and having a pinion 21 on its inner end engaging a gear 22 on the shaft 15. A ratchet wheel 23 and holding pawl 24 prevent backward rotation of the 65 shaft 15.

A plurality of tapered winding rolls 25 are loosely supported on the shaft 15 and each roll has a hub or shoulder 26 on which a friction clamp 27 is mounted. A spring 28 (Fig. 5) forces the two parts of the 70 clamp yieldingly against the shoulder 26 and the pivot-pin 29 of the clamp is extended to enter a recess in a driving arm 30 fixed to the shaft 15. Each roll 25 is thus yieldingly 75 connected with the shaft 15.

In practice it is customary to rotate the shaft 15 at a slightly higher speed than is necessary to take up the cloth on the rolls 25, the rolls slipping to permit the additional angular movement of the shaft. 80

The parts thus far described are the usual type and form no part of my present invention, which relates particularly to the provision of improved take-up mechanism mounted on the breast beam and closely adjacent 85 the fell of the cloth at the forward position of the lay 12.

This improved take-up mechanism comprises a plurality of take-up rolls 31, 32 and 33 mounted in bearings in a bracket 34 and 90 mounted as a unit on the breast-beam 11. The take-up rolls are each provided with a sprocket 35 having driving engagement with a chain 36, which in turn is driven by a sprocket 37 on the winding shaft 15. The 95 chain engages the sprockets of the take-up rolls as shown in Fig. 2, and the path of the fabric F around the rolls is clearly shown in Fig. 4, in which the direction of rotation of the different rolls is also indicated. These rolls are positively rotated with the shaft 15 and place the desired tension upon the fabric and warp at a point 100 closely adjacent the fell of the cloth.

This location of the take-up rolls near the 105 fell of the cloth is very important, as the inequality in length of the two sides of the fabric at this point is so slight that it does

not seriously interfere with providing uniform tension throughout the width of the cloth. If, however, the tension is applied at a point more remote from the lay, the 5 inequality in the length of the cloth at different points in its width interferes seriously with providing uniform tension therefor.

Having thus described my invention, I do not wish to be limited to the particular 10 tails herein shown otherwise than as set forth in the claims.

What I claim is:—

1. In a narrow ware loom, in combination, a loom frame, a lay, a plurality of relatively small tapered take-up rolls mounted on said frame adjacent the extreme forward position of said lay, and means to drive said rolls, said rolls being spaced apart and having their axes parallel, and said driving 15 means comprising a single continuous driving member moving in a closed path and successively engaging all of said rolls and rotating adjacent rolls in opposite directions.
2. In a narrow ware loom, in combination, 20 a loom frame, a lay, a plurality of relatively small tapered take-up rolls mounted on said

frame adjacent the extreme forward position of said lay, and means to drive said rolls, said rolls being spaced apart and having their axes parallel and adjacent rolls being rotated in opposite directions, and said driving means comprising sprockets on said rolls, a sprocket chain successively engaging different sprockets, and means to drive said chain.

3. In a narrow ware loom, in combination, a loom frame, a lay, a plurality of relatively small tapered take-up rolls mounted on said frame adjacent the extreme forward position of said lay, and means to drive said rolls, said rolls being spaced apart and having their axes parallel and adjacent rolls being rotated in opposite directions, and said driving means comprising sprockets on said rolls, a sprocket chain engaging successive 40 sprockets on alternate sides of said chain to rotate said sprockets in opposite directions, and means to drive said chain.

In testimony whereof I have hereunto affixed my signature.

ELBRIDGE R. HOLMES.
